EMULSIFYING DEVICE

Herbert C. Johnson, Chicago, Ill.

Application December 6, 1934, Serial No. 756,210

7 Claims. (Cl. 99—267)

My present invention relates to a device which may for convenience in describing it be termed a "creamer", devised more particularly for the purpose of forming from butter and either skimmed milk, or unseparated natural milk, an emulsion rich in butter fat, and corresponding in character to cream, of such richness as may be desired. The object of my invention is to provide a simple and inexpensive device of this character, suitable for household use and which, by reason of structural features in the mechanical construction of the parts, shall function in a most efficient manner and be highly useful and desirable in attaining the desired results. With this purpose in view I have designed and invented the emulsifying device, or creamer, hereinafter described in detail, and my invention resides in the novel construction and arrangement of the parts, combined and cooperating as described, as hereinafter more particularly pointed out in the appended claims.

In the accompanying drawing I have illustrated my invention in a preferred form, and also illustrated a modified construction of certain of the elements thereof.

Figure 1 is a front view of the preferred form of my invention, the bowl of the creamer being shown in section to show the parts arranged therein;

Fig. 2 is a side elevation of the same, certain of the parts being shown in section;

Fig. 3 is a vertical section of the principal working parts of the device, in planes indicated by the broken dotted line 3—3 of Fig. 2; viewed in a direction indicated by the arrows; and

Fig. 4 is a horizontal detail section, in a plane indicated by the dotted line 4—4 of Fig. 3.

Fig. 5 is a detail vertical section of a modified construction of the lower end of the cylinder and the nozzle of the device; and

Fig. 6 is a horizontal detail section of such modified form of my invention, in a plane indicated by the dotted line 6—6 of Fig. 5.

Like reference characters indicate like parts in all the figures of the drawing.

The supporting frame of my creaming device may conveniently include, as illustrated, a horizontal plate 1, adapted to support a pitcher or other receptacle, continuous at the rear with a vertical bracket plate 2, which may be formed of any suitable strong and preferably light material, such as cast aluminum. The top of the bracket 2 is formed with a socket adapted to receive a pin 3 secured to a block 4 formed on the

lower side portion of a bowl 5, preferably formed of metal.

The top of the bowl 5 is formed with bearing lugs 6—6 arranged to receive the ends of a shaft 7 formed with a central bend 8 to serve as a crank for transmitting power to the operating parts hereinafter described. To one end of the shaft 7 is secured an operating crank 9 equipped with a handle 10 by which the crank may be rotated.

Describing now the parts directly concerned in producing emulsification of the butter and milk, the lower end of the bowl is formed with an axial boss 11 arranged to receive a cylindrical plug 12 which, as shown, extends upwardly into the bowl a short distance and is formed with a central bore or cylinder communicating through a circular row of orifices 12a with the space inside the bowl at its lowest portion. The lower end of the plug 12 is exteriorly screw-threaded to provide a readily detachable connection for a removable nozzle 13. The lower end of the plug 12 is formed with a small axial bore 14 arranged to receive a pin 15 fixed centrally to the top of the nozzle 13 and slightly smaller in diameter than the bore 14 of the plug, thus providing an annular passageway around the pin of small dimensions. It will be noted that when the nozzle is removed the bore 14 is unobstructed and is of such capacity as to form a drain opening of restricted size, but larger than the emulsifying annular passageway provided when the nozzle is secured to the cylinder.

The top of the nozzle and bottom of the plug are centrally counterbored around the axis of the parts to form an axial chamber 16 (see Fig. 3) and the bottom of the chamber communicates through a pair of small converging channels 17—17 in the nozzle with the discharge orifice 18. It is obvious that the chamber 16 may be formed wholly in the top of the nozzle, or bottom of the plug, if desired.

Within the chamber 16 and surrounding the pin 15 is arranged a washer 19 which is formed of soft rubber of a character not affected materially by a moderate degree of heat, and of a compressible and elastic nature. This washer is of such thickness that when the device is not being operated and the parts are at rest, the washer contacts at top and bottom with the opposed upper and lower walls of the chamber 16, and preferably is under slight compression.

The central bore or cylinder of the plug 12 is arranged to slidably receive a plunger 20 which is formed with ears 21—21 at its top to provide a

pivotal connection with a link 22 pivoted to the bend 8 of the actuating shaft, whereby reciprocation of the plunger 20 in the cylinder of the plug may be effected. The arrangement is such that at the top of the stroke of the plunger the orifices 12^a of the cylinder will be uncovered, while at the bottom of its stroke the lower end of the plunger will extend nearly, but not quite, to the bottom of the cylinder.

10 The top of the plunger 20 carries an agitator 23 having a flat top slotted to accommodate the movement of the link 22 and a flaring or funnel-shaped skirt extending downwardly which in lowermost position extends to within a short distance of the bottom of the bowl 5. The agitator may conveniently be secured to the plunger by a pair of screws seated in the ears 21, as shown, — see Figs. 3 and 2.

15 The procedure followed in operating the device will now be described before explaining the operation of the mechanism. It will be understood that the butter operated upon may be either salted or unsalted, though a slightly different procedure is followed in the different cases.

20 About one-eighth of a pound of butter to one pint of milk may be used to produce a cream of ordinary richness. If unsalted butter is used the milk and butter are heated and stirred together until the butter is melted, though the mixture should not be allowed to boil. The mixture so prepared is then ready to be put through the machine.

25 If salted butter is used the butter is boiled with a sufficient quantity of water until the butter is melted and then is placed in the creamer and the nozzle 13 removed, which will permit the water (which has then taken up the salt) to drain out through the drain opening in the bottom wall of the cylinder. As soon as the water has drained off (which can be detected by the change of color in the stream), the nozzle is replaced and the heated milk placed in the bowl, and the mixture may then be pumped through as in the case first described, the mixture coming through the nozzle 40 in the emulsified creamy state desired.

30 If a richer cream be desired the proportion of butter may be increased, a proportion of about one-fourth pound of butter to one-half pint of milk resulting in a rich "whipping" cream.

35 The operation of the pumping mechanism, constructed as hereinbefore described, as is follows:

40 Assuming that the cylinder 12 is full of a mixture of melted butter and milk and the piston 5 is descending from the top of its stroke, the interior of the cylinder is shut off from the inside of the bowl as soon as the piston closes off the ports or orifices 12^a, and the mixture trapped below it is placed under pressure which forces it downwardly through the annular passage around the pin 15, the washer 19 yielding slightly as the mixture is squeezed laterally over and past it to the annular space at the outer edge of the washer, whence it passes through the pair of small passages 17 to the discharge orifice of the plug. The 45 mixture is thereby thoroughly emulsified in its passage from the cylinder to the plug outlet.

45 On the upward stroke of the plunger the washer 19 acts as a valve to prevent any substantial quantity of the mixture below it in the nozzle, or air from the outside, from returning to the cylinder, and the pressure in the cylinder is reduced until the ports 13^a are opened, when a further charge of the mixture is quickly sucked in and the operation above described is repeated.

50 In Figs. 5 and 6 I have illustrated a construc-

5 tion of the discharge passages through the lower end of the cylinder, marked 30, and the plug, marked 31, which is entirely valveless. In this construction the lower end of the cylinder is formed with a plane face, and the central portion of the upper face of the plug is formed with small radial channels 32 (four in number in the present instance) extending outwardly from the small central pin, marked 33, and at their outer ends communicating with small vertical channels 34 10 leading into a common discharge orifice 35. The capacity of the annular channel around the pin 33 and the channels 32 and 34 is so small, relatively to the displacement of the plunger, that upon the downward movement of the plunger the 15 mixture is forced out at high pressure and speed through these small passages, whereby it is effectively emulsified, while upon upward stroke of the plunger but a small quantity of the mixture in the discharge orifice of the plug and of outside 20 air can enter to relieve the vacuum created on the upstroke before the piston clears the orifices or ports at the bottom of the bowl and a fresh charge of mixture is drawn into the cylinder.

25 It is obvious that in this construction the radial channels 32 may be formed in the lower face of the cylinder, instead of in the top of the nozzle, if desired.

I claim:

1. An emulsifying device comprising a bowl, a 30 plug at the bottom of said bowl formed with a cylinder having ports communicating with said bowl and having a vertical orifice at its bottom, a plunger in said cylinder controlling said cylinder ports, a nozzle secured to said cylinder and 35 equipped with a vertical pin extending into said orifice and of slightly smaller diameter, said nozzle being formed with a central discharge orifice and also with emulsifying passages of small dimensions extending radially from the annular 40 space around said pin and communicating with small vertical emulsifying passages which open into said central discharge orifice.

2. An emulsifying device comprising a bowl, a 45 plug at the bottom of said bowl formed with a cylinder having ports communicating with said bowl and having a vertical orifice at its bottom, a plunger in said cylinder controlling said cylinder ports, a nozzle secured to said cylinder and 50 equipped with a vertical pin extending into said orifice and of slightly smaller diameter, said nozzle being formed with a central discharge orifice and also with a radially-extending emulsifying passage communicating with the annular space around said pin and also communicating with a 55 plurality of small downwardly extending emulsifying passages which communicate with said discharge orifice.

3. An emulsifying device comprising a frame 60 plate including a horizontal supporting stand portion and a rear vertical bracket, a bowl supported by said bracket and having a ported emulsifying cylinder extending vertically through its bottom, a discharge nozzle secured to the lower end of said cylinder above said supporting stand portion of 65 the frame, said nozzle and the lower end of said cylinder being provided with small emulsifying passages, a plunger in said cylinder cooperating with the cylinder ports and equipped with an agitator secured to its top formed with a depending flange arranged to approach into proximity with the inside of the bowl at the limit of its downward movement, an operating handle and shaft rotatably mounted in bearings carried by 70 the upper portion of said bowl and having a 75

central crank portion, and a link pivotally connecting said crank portion and the top of said plunger.

4. An emulsifying device including a stationarily supported bowl having an emulsifying cylinder extending downwardly from its bottom, said cylinder extending also upwardly inside said bowl, a nozzle communicating with said cylinder formed with small emulsifying passages and with a communicating discharge opening, a reciprocating plunger in said cylinder equipped with an agitator, said agitator having a flat top portion secured to the top of the piston and a depending funnel-shaped flange portion arranged to descend nearly to the inside of the bowl at the lowermost point in its travel.
5. An emulsifying device including a bowl, a cylinder having ports communicating with said bowl and formed with a centrally orificed bottom wall, a reciprocating plunger in said cylinder arranged to govern said cylinder ports, a nozzle secured to the bottom of said cylinder and provided with a pin extending into and of smaller diameter than the orifice of said bottom wall, 10 said nozzle and/or bottom cylinder wall being formed with a plurality of small radial emulsifying channels communicating with the annular space about said pin and said nozzle being formed with a like plurality of channels communicating with said radial channels and with the discharge opening of the nozzle.
6. An emulsifying device including a bowl, a cylinder having ports communicating with said bowl and formed with a centrally orificed bottom wall, a reciprocating plunger in said cylinder, 15 arranged to govern said cylinder ports, a discharge nozzle at the bottom of said cylinder provided with a pin extending into and of smaller diameter than the orifice of said bottom wall, said nozzle and/or bottom cylinder wall being formed with a shallow recess concentric with said central orifice, an elastic compressible member arranged within 20 said chamber and normally yieldingly contacting portions of the upper and lower walls of said chamber, said member yielding under liquid pressure while the plunger is descending and expanding on the upward stroke of the plunger to prevent return of liquid upwardly.

cylinder having ports communicating with said bowl and formed with a centrally orificed bottom wall, a reciprocating plunger in said cylinder arranged to govern said cylinder ports, a nozzle secured to the bottom of said cylinder and provided with a pin extending into and of smaller diameter than the orifice of said bottom wall, 5 said nozzle and/or bottom cylinder wall being formed with a plurality of small radial emulsifying channels communicating with the annular space about said pin and said nozzle being formed with a like plurality of channels communicating with said radial channels and with the discharge opening of the nozzle.

7. An emulsifying device including a bowl, a cylinder having ports communicating with said bowl and formed with a centrally orificed bottom wall, a reciprocating plunger in said cylinder, 10 arranged to govern said cylinder ports, a discharge nozzle at the bottom of said cylinder provided with a pin extending into and of smaller diameter than the orifice of said bottom wall, said nozzle and/or bottom cylinder wall being formed with a shallow recess concentric with said central orifice, an elastic compressible member arranged within 15 said chamber and normally yieldingly contacting portions of the upper and lower walls of said chamber, said member yielding under liquid pressure while the plunger is descending and expanding on the upward stroke of the plunger to prevent return of liquid upwardly.

HERBERT C. JOHNSON.
